CLAIM

The ornamental design for a video tape recorder, as shown and described.

DESCRIPTION

FIG. 1 is a perspective view of a video tape recorder showing my new design;

FIG. 2 is a top plan view thereof;

FIG. 3 is a left side elevational view thereof, a right side elevational view thereof being a mirror image; and,

FIG. 4 is a front elevational view thereof, the rear elevational view being unornamented.
